UNITED STATES PATENT OFFICE.

RENO DE ORVEILLE JOHNSON, OF PALMYRA, NEW JERSEY, ASSIGNOR OF ONE-FOURTH
TO JOSEPH G. SEEL AND ONE-FOURTH TO ALVAN E. SWAIN, BOTH OF PALMYRA,
NEW JERSEY.

AUTOMATIC FIRE EXTINGUISHER.

Application filed October 29, 1921. Serial No. 511,437.

To all whom it may concern:

Be it known that I, RENO DE ORVEILLE JOHNSON, a citizen of the United States, residing at Palmyra, in the county of Burlington, State of New Jersey, have invented a new and useful Automatic Fire Extinguisher, of which the following is a specification.

My invention relates to fire extinguishers, 10 which are especially adapted for use with automobiles. The object is to provide a simple and inexpensive device that will act automatically under the influence of heat and flame, to extinguish the flame that causes its action. The object is also to produce a device that will be safe and efficient.

Referring to the drawings which illustrate merely by way of example, a suitable embodiment of my invention;

20 Fig. 1 is a section showing my device ready for action.

Fig. 2 is a similar view, after the keeper has been melted and the fuse projected, as into the flame area.

25 Fig. 3 is a side elevation of the device as shown in Fig. 1.

Fig. 4 is an end elevation of the same.

Fig. 5 is a view in perspective on a reduced scale, showing the device mounted in 30 a suitable holder.

Similar numerals refer to similar parts throughout the several views.

The container for the fire extinguishing powder comprises the cylinder 6, and the 35 end pieces or caps 7 and 8. These elements may be made of paper fibre or similar material suitably coated to render them moisture proof. The end piece 7 is provided with the opening 9 for the introduction 40 of the powder or other fire extinguishing material 10 into the receptacle. This opening 9 is then closed by the covering piece 11, glued or otherwise securely secured to the end piece 7. The end piece 8 is also 45 provided with a central opening for receiving the flanged cylindrical member 12 having the flange 13 and the mortised recess 14. A cylinder or cartridge 15 is fitted into member 12 and projects centrally well 50 into the body of the cylinder 6. The cartridge has at its innermost end a small charge of explosive, such for example gun powder, as at 16, secured in place between the plug 17 and the closing cap 18. The 55 plug 17 is provided with a channel 19 ex-

tending longitudinally entirely through the plug 17. A fuse 20 extends from the charge of the explosive 16 through the plug 17, and the balance of its extension is coiled or folded in the chamber 21 formed within cartridge 15 between the plug 17 and the outer end of the cartridge. A helical spring 22 is seated in the space 23 formed between the cartridge 15 and an offset portion of the member 12. The outer end of spring 22 is connected to the outer end of fuse 20. The spring 22 is normally maintained compressed by a keeper 24. This keeper 24 is inserted through the notches 25 and then turned in the mortised opening 14 into the 70 position as shown in Fig. 4. This keeper is made of a suitable material such as an alloy of metal having a fusing or melting point suitably high safely to resist a temperature considerably above the normal temperatures 75 of the spaces in which the device is mounted but sufficiently low to melt when an abnormal temperature occurs in said space due to a fire.

The device is mounted in any suitable 80 frame or bracket such as the frame comprising the two loops or rings 26 secured to the arm or extension 27. The arm 27 is bolted or otherwise secured to a part of the frame work of the case beneath the hood. 85 These rings 26, which are preferably of spring metal, have the reverse bends 28 which upon pressure cause a slight expanding of the rings to admit the enlarged ends or caps 7 and 8, whereupon when said pressure is released the rings contract and hold the receptacle, formed by cylinder 6 and end pieces 7 and 8, as clearly shown in Fig. 5.

In operation:

When the device is suitably positioned on the car preferably near the engine and carburetor and beneath the hood, it may be carried without injury as long as normal 100 conditions are maintained. When however a fire occurs in the space approximate said device the keeper 24 is melted, the spring 22 is released and the fuse 20 is extended by the spring, across a very extended area affected by the flame. Obviously the fuse coming into contact with the flame, becomes 105 ignited and burns until it has ignited the explosive charge 16. This results in an explosion which causes a bursting of the cylinder 6 and an effective distribution of the 110

extinguishing substance 10, throughout the flaming area and thus smothers and extinguishes the fire. In order to assure an even disintegration of the cylinder 6, I prefer 5 to provide the cylinder walls with a plurality of evenly disposed staggered slits 29 as shown in Fig. 2. A thin strip or coating of impervious material is applied to the inner or outer wall of the cylinder, to prevent 10 the passage of the material or of air or moisture through the slits 29.

It will be understood that the device may be placed in any desired space where a fire may occur and it may be so positioned, with 15 respect to the direction of its axis as to project the fuse in the direction in which the hottest or first flame is likely to occur, or two or more such devices may be placed to be affected by a flame in a given area 20 and to project their fuses in different directions. It will also be understood that the charge of explosive necessary to burst the container and distribute the extinguishing substance over the required area, need be 25 very small, and therefore there is no danger whatever attending such explosion.

All of the elements except the keeper and bracket may be made of paper and other fibrous substances and at very small expense, 30 so that the cost of installing and maintaining this very efficient automatic protection against fire is almost negligible or at least out of all proportion to the value of the protection secured.

What I claim is:—

1. The combination of a container, a charge of fire extinguishing substance in the container, an explosive charge also within the container, a fuse in communication with the explosive and folded in proximity to 40 said charges, a spring connected to the fuse and normally held under compression by a fusible keeper, adapted upon release by the keeper to project the fuse in any given direction. 45

2. The combination of a container, a charge of fire extinguishing substance in the container, an explosive charge also within the container, a fuse in communication with the explosive and folded within the container, a spring connected to the fuse and normally held under compression by a fusible keeper, adapted upon release by the keeper to project the fuse in any given direction. 50

3. The combination of a container, provided with a plurality of slits spaced apart throughout its peripheral wall, and covered with a coating of water proof material, a charge of fire extinguishing substance in 60 the container, an explosive charge also within the container, a fuse in communication with the explosive and normally confined within the container by a fusible keeper, and resilient means for projecting the fuse 65 from the container upon release by the keeper.

RENO DE ORVEILLE JOHNSON.
